UNITED STATES PATENT OFFICE.

ALEXANDER DICK, OF MERIDIAN, NEW YORK.

ADDRESSING-MACHINE.

SPECIFICATION forming part of Letters Patent No. 629,241, dated July 18, 1899.

Application filed May 4, 1896. Serial No. 590,171. (No model.)

To all whom it may concern:

Be it known that I, ALEXANDER DICK, a citizen of the United States, and a resident of Meridian, in the county of Cayuga and

5 State of New York, have invented certain new and useful Improvements in Addressing-Machines, of which the following is a specification.

This invention relates to improvements in addressing-machines of the class commonly known as the "belt-feeder" and "automatic labeler" and of which my brother, Robert Dick, his first patent being numbered 64,502 and dated October 4, 1857, was the original 15 inventor and patentee. The chief points of these improvements are given more specifically as follows: first, a better form of shell, being the same as that of my star-mailer, which is altogether a slideway-feed machine, 20 patented September 18, 1877, No. 195,209; second, in combination with a belt-feed movement, a short slideway between it and the cutting-blades, by which the handle and propelling-roll are brought back to a higher position in the descent toward the cutters, allowing space between said roll and the projecting ends of the cutters, thus not requiring the roll to be placed inconveniently at a 25 point beyond said ends as formerly and at the same time permitting the motor-arm to occupy a position adjacent to the shell directly under the hand of the operator and in line of its action and not at a distance and eccentric thereto, as formerly in machines 30 of this belt-feed and automatic kind; third, instead of a heavy metallic roller to give tension to the belt a light tension-roller added with spring action gives a better result; fourth, by the employment of a large metallic 35 paste-roller, hollow and light, like that of my star-mailer already referred to, turning in fixed bearings, which may be sprung a little from each other, around which roller the paste-belt passes and over the tension-roller, 40 close thereto in front above the paste, no paste gets inside the belt, which in other machines causes trouble; fifth, a new and improved form and attachment of thumb-balancer; sixth, a new and improved application 45 of cross-bar for bringing the web of addresses in connection with the pasting-belt; seventh, a greatly-improved connection of

the vibrating blade with its operating-lever and check at proper elevation; eighth, an improved mode of regulating the paste upon the 55 paste-belt.

For those skilled in the art the following description will be sufficient, reference being had to the accompanying drawings, in which the same letter always designates the same 60 part.

Figure 1 is a top plan view of this machine. Fig. 2 is a side view of the same from the left. Fig. 3 is a front view with belt and blades removed. Fig. 4 is a view of the vibrating 65 blade with the parts to which it is attached. Fig. 5 is a view of the paste-regulator and spring. Fig. 6 is a detached perspective view of one end of the paste-roller bearings. Fig. 7 is a cross-section view of propelling-cylinder. Fig. 8 is a detached perspective view 70 of the motor-arm. Fig. 9 is a central longitudinal and vertical section view of this improved addressing-machine.

As already stated, the shell or supporting-frame of this addressing-machine is like that of my star-mailer and is composed of a rear address-holding compartment, a middle paste-holding compartment, and a forward supporting-frame portion, as seen in Figs. 1 and 2, 80 having the rear end plate marked E, Fig. 3, the middle division-plate K, and front plate. In the rear compartment is the roll and spindle O O', upon which the web of printed addresses is reeled. In the middle compartment is the large paste-roller X, made of thin plate metal hollow and light, having the ends of its axis projecting a little and journaled in openings in the ends of a strip of flat spring metal that is secured transversely to the bottom of the shell with its ends turned up at an angle near the sides of the shell, thus permitting the bearings to be sprung a little apart, but not otherwise, to receive as journals the ends of the axis of paste-roller X, 85 having its lower part within, but the upper and main part above the surface of the paste. These bearings are seen at the points e e, Figs. 1 and 6. The tension-roller R, Figs. 3 and 9, has the ends of its axis turning on 90 springs S S, Figs. 1 and 9, that give it the necessary upward pressure against the belt B when in position to secure action. These springs at their lower end are secured to the

shell by soldering or otherwise, one on each side within the shell, their upper ends being turned into hooks or circular openings to receive as bearings the ends of the wire axis of the tension-roller and so located that when the roller is put in position it will lie close to and parallel with paste-roller X and entirely above the paste. In Figs. 1 and 3 these bearings are marked *o o*. The pasting-belt B may consist of any suitable material. Vulcanized-rubber steam packing is good, but must be of the thinnest kind. Having placed the paste-roller X in the end of the belt, spring the ends of its axis into their bearings, and the tension-roller being in place, with the cylinder C, having spurs on its surface, Fig. 7, placed in the end of the belt, bring it forward and over the tension-roller R and front plate I of the paste-compartment down till the tension-roller acts on the belt. Then insert the shaft into its bearing on the left side of the shell at *d*, Fig. 1, and push it into and through the cylinder into its bearing *d'* on the right side of the shell. This shaft has upon its end the finger piece or roll F, as seen in the figures. It must pass with some degree of fixedness into the propelling-cylinder C, which has upon it the shoulders *c c*, one each side the belt to retain it in position. If now the finger-piece E be revolved, the cylinder and belt will also be revolved easily and truly. As will be seen from the figures, there is an intervening space between the belt movement and the stationary blade G. Filling this space is a ribbed or corrugated slideway M, Figs. 1 and 3, to support the web of addresses as it passes from the belt and propeller down to the cutters. This slideway rests upon and is secured to a metallic plate bent in the form of a half-cylinder, with its open side forward and secured to the shell, as seen in Figs. 3 and 9 and marked *y*. By this combination of slideway and pasting-belt movement three important points are gained—viz., first, by bending the front of plate *y*, on which the slideway rests, down or up a true delivery of the address-web is attained into the cutters whatever may be the change in height of stationary blade G, for grinding changes it; second, the propeller, with its feed-roll F, is at some distance from the cutters and also above the plane in which the bottom of the shell lies, so that the feed-roll F occupies a better position for operating, not being placed inconveniently in an outward position low down and beyond the projecting ends of the cutters, so as to avoid them, as formerly, and, third, space is allowed for the action of the motor-arm adjacent to the shell under the hand of the operator, its best position, which could not be formerly and so had to be placed beyond and eccentric to the action of the hand operating the machine and at a distance removed from its center of gravity.

The weight of the machine itself supplies the main power required for the cutting off and stamping on of the addresses in its automatic

action, and hence the importance of having the motor-arm, which is effective by acting upon the underlying substance as a fulcrum, come as near to the center of gravity of the machine as possible and directly under the hand of the operator.

The motor-arm *J' J*, Figs. 1, 2, and 3, made of stiff spring-wire, is hinged in the rear end of the shell by passing through it at opposite points *h h'* near the bottom. It is then brought forward contiguous to the shell on the left side, and near the projecting end of the stationary cutter G is bent outward and around in front of the cutting-blades, and at P is doubled up over itself, but openly, and is continued and brought around until it intersects the line of direction of the stationary blade G a little beyond its extremity. At *p* it again doubles up over itself with a somewhat sharp turn with a short point looking directly forward, which point projects through a shoulder *t*, beyond which it is received as a movable axis of force in the end of lever *a* at *u*, connecting with the vibrating, cutting, and stamping blade W. This blade, Fig. 4, is a highly-tempered steel plate ground and polished, as required. Its bearer *a* has an extension-lever *a'*, which is preferably cast in one piece of brass and is so formed as to receive the bolt I, on which the two parts *a* and *a'* are hinged, together with the blade W. This is joined to *a* easily and truly by soldering, if carefully done, without drawing its temper. The bolt after passing through the brass casting is screwed into and through the stationary blade G, and when attached to the machine the protruding end is slipped through the ear *g*, Figs. 1 and 3, and a nut *n*, screwed up firmly in the rear, holds the bolt and blades securely in position, the other end of the stationary blade being held in the socket *g'*. Both cutting-blades are made of comparatively thin steel, and the bearer *a* has a shoulder *b* to keep the cutter-stamp W, which lies flat horizontally, from catching under the stationary blade when brought down. The handle of this machine, D, as seen in the figures, is formed of wood and fastened to the left side of the shell with screws. This has long been a common device; but I put with it a balancer that is new in form and attachment and with new capabilities. It is marked H in the figures and is made of thin but stiff metallic plate, is placed between the wooden handle and the shell, and held and pivoted there by passing through it the forward attaching-screw *v* of the handle. Thus pivoted and held it is readily brought to any position required by the size of hand or fancy of the operator. Its use as a balancer is to supply a brace to the thumb of the left-hand that operates the machine, so that it may more easily be held at the necessary level. Outside the shell on the left and toward the rear there is a spring *y*, secured to the shell, as shown in Fig. 2. Its lower end is turned outwardly and formed to

rest as a foot upon the motor-arm J, on which it has downward spring action.

The cross-bar L, Figs. 1 and 2, is placed so as to hold down the web of addresses as it passes from the reel to the pasting-belt B and bring it in contact therewith. It may be supplied with shoulders *i i*, which confine the web in proper direction. The spurs *r r* upon the slideway M perform a like function. The 10 end of bar L on the left is turned at a right angle, which part is hinged in a socket that is secured longitudinally to the upper edge of the shell at *w*. Thus the bar can instantly be laid over out of the way, if desired, as seen in Fig. 3, and again instantly brought in use. This is a new and important device found in no other addressing-machine.

The paste-regulator V, Fig. 5, is made of a narrow strip of metal the length of the paste-roller X, with tooth-indentations on its edge and preferably on both edges, the indentations being somewhat greater on one edge than on the other, so as to allow more or less paste upon the belt. The regulator being reversible, it is soldered longitudinally to a wire *s s*, the ends of which are bent, as shown in the figure, constituting spring-arms, which again at equidistances are bent outwardly in opposite directions and which with short 25 points are sprung into bearing-openings on each side of the shell or supporting-frame near its upper edge and exactly opposite, as seen at *m m*, Fig. 1, and also adjusted that the narrow serrated plate will come edgewise along 30 and against the rear side of paste-roller X and of course across the pasting-belt B when in place. The spring V has its upper part bent over the upper edge of the rear plate of the paste-holding compartment at its central point and so formed as to hold its position 35 by its own spring action. The lower end is in spring contact with the paste-regulator to hold it lightly with spring tension against the belt. It will be observed that the shoulder 40 *t* upon the end of the motor-arm J' is to communicate spring-pressure, which it receives from the motor-arm, to the end of lever *a'* and thence to the vibrating cutting-blade W against the stationary cutting-blade G and 45 that according as this point of the motor-arm is sprung more or less forward more or less cutting pressure is communicated to the cutting-blades against each other. This, however, is not novel; but the mode by which I 50 check the elevation of the vibrating blade at the proper point is novel and complete, which is as follows: I have before said that the bend in the end of the motor-arm wire at *p* should be somewhat sharp; but it should be such as 55 to leave a little space between the lower edge of lever *a'*, through which the wire point projects as a motor-axis, and the underlying wire. The end of lever *a'* I make to project a little beyond motor-axis *u* and in excess of the space 60 or opening between the point and wire over which it is bent, and I so adjust the whole 65 that when the vibrating blade rises by the de-

scent of lever *a'* it will be stopped at the proper elevation by the projecting end of lever *a'* coming in contact with the underlying wire of the motor-arm. Heretofore in the best machine having this kind of automatic action the uncertain and excessive elevation of the vibrating blade has sometimes been very annoying to the operator, as is also the loose and unsightly attachment of the lever to a heavy vibrating blade.

From the foregoing description the action of this improved addressing-machine in all its parts must be apparent. Let then these 70 parts be in their true and relative condition, with web of addresses reeled in its place, pour suitable paste in proper quantity into the paste-box in rear of the paste-roller X. Now by means of the finger piece or roll F of the 75 propeller revolve the belt forward. The paste-regulator will keep back the superfluous paste, leaving the desired quantity upon the belt, and there will be none inside of it, for it closely hugs the paste-roller while passing 80 through the paste. Now bring forward the end of the address-web and lay it in position upon the pasting-belt. Bring over the hinged bar L upon the web. Now take the machine in the left hand, grasping the handle D in the 85 palm, with the forefinger upon the propeller-roll F and the thumb inside the balancer H. With the machine thus in hand resting upon the pile of papers or articles to be addressed raise it a little. The action of spring Y upon 90 the motor-arm J J' will press it downward, which at the same time acting upon the end of lever *a'* at *u* will bring it down, and thereby raise the cutter-stamp W to the proper elevation, it being there stopped by the outer 95 point of lever *a'* coming in contact with the underlying wire of the motor-arm. The conditions are now proper for feeding the address-web into the cutters. Receiving paste on its 100 under side from the pasting-belt, and thus adhering thereto, it is fed forward by the action of the finger upon the feeding-roll F and is pushed down the ribs of the slideway M, which it lightly touches, into the cutters one address. Now drop the machine, with a little 105 pressure, if necessary, upon the paper beneath. This has become a fulcrum to the motor-arm, the pressure of spring Y has been overcome, and reverse action of axis upon lever *a'* has pushed it up and brought down the 110 cutter-stamp W, which, in conjunction with the stationary blade, has cut off the address and affixed it upon the underlying paper, which the right hand at once removes, and the operation, automatic to the fullest advantageous extent, it is believed, is repeated *ad libitum*.

It may be observed that if the addresses are put upon the upper edge of the pile of papers removed from the operator, as is common, then the paper under the motor-arm adjacent to the shell in the forward part under the operator's hand becomes its fulcrum; but if the addresses are put on the lower edge

of the papers next to the operator then the paper under the motor-arm in front of the cutters becomes its fulcrum. I do not claim invention for everything presented in the foregoing description; but

What I do claim, and desire to secure by Letters Patent, is—

1. In an addressing-machine, the combination with the supporting-frame provided with bearing-openings in its sides, the front and rear paste-belt-supporting rollers mounted in said frame, the paste-holding compartment and the paste-belt, of a paste-regulating device or scraper provided with spring-arms 15 adapted to be sprung into the bearing-openings in the supporting-frame and a spring having its upper end bent over the top edge of the rear wall of the paste-holding compartment, and its opposite end in engagement with 20 said scraper to hold it with a spring tension against the paste-belt, the said scraper being reversible and provided with two serrated edges, as set forth.
2. In an addressing-machine, the combination of the supporting frame or casing, the paste-holding compartment, the paste-belt, the front belt-supporting roller, the rear belt-supporting roller, a supplemental tension-roller mounted in spring-bearings, a reversible 25 double-serrated-edge scraper hung loosely from bearings near the top of the side walls of the paste-holding compartment and a spring having its upper end bent over the top edge of the rear wall of the paste-holding compartment and its opposite end in spring 30 contact with the scraper to press it with a spring tension against the belt.
3. In an addressing-machine, the combination with the casing comprising the rear compartment, the paste-holding compartment and the forward compartment, two curved springs each rigidly secured at its lower end to one of the inner sides of the casing, and having its upper end bent in a hook form, and 35 a supporting portion turned transversely on the bottom of said casing and provided with spring ends bent upward at an angle therefrom and forming bearing portions, of a main belt-carrying roller adapted to be sprung into 40 and supported in a fixed position in the spring ends of the supporting portion, with the bearings above the surface of the paste and its lower surface immersed within, a forward belt-carrying roller supported in the forward 45 compartment of the casing, a tension-regulating roller adapted to be sprung into the hooked ends of the curved springs, and held thereby entirely above the surface of the paste, and a paste-belt partially encircling and 50 supported by the main roller and the forward supporting-roller, and held with a spring tension against the main roller by the spring-supported regulating-roller, and especially 55 against the roller beneath the paste, thus preventing the paste from reaching the inner surface of the belt, as set forth.
4. In an addressing-machine, comprising a

shell composed of a rear address-holding compartment, a middle paste-holding compartment, and a forward frame portion, a roller-supporting portion secured to the bottom of the paste-holding compartment and having its ends bent substantially vertically upward at a short distance inwardly from the sides of the frame to form spring-arms which are movable toward or from each other only and are provided with openings near their top, a main roller having the two ends of its axis extended a little and adapted to seat and journal in the openings in the spring-arms, a cylinder provided with a serrated periphery and forming a forward roller, a shaft passed through the sides of the forward frame portion and the cylinder and having a portion protruding on the exterior, a finger-piece supported on said protruding portion, and a belt passed partially around the main roller, and the forward roller and a tension-roller located between the main roller and the forward roller, spring portions having their lower ends secured to 90 the interior of the shell and their upper ends bent to partially encircle and support the tension-roller, and adapted to press said tension-roller upward against the belt, as set forth.

5. In an addressing-machine of the class described, having a motor-arm for effecting automatic action, a side handle-grip and a belt-feeding roller, the combination of the shell-frame, the cutting mechanism supported at the front of the shell-frame, a main roller, a 100 forward feeding-roller, a pasting-belt supported upon the main roller and the forward feeding-roller, an auxiliary side feeding-roller rigidly mounted upon the shaft of the forward feeding-roller, and a slideway in front 105 of the feeding-belt and interposed between the cutting mechanism and the forward feeding-roller, whereby the belt-feeding roller and the side feeding-roller are elevated above the plane of the shell-bottom, and also removed 110 back from the cutting mechanism sufficiently to afford the motor-arm place and room for action adjacent to the shell under the hand of the operator, substantially as set forth.

6. In a label-addressing machine, having a 115 motor-arm for automatic action of the vibrating cutting-blade with a connecting-lever the end of which receives the end of the motor-arm bent over upon itself and forming the axis therefor, means for checking the vibrating blade at the proper elevation consisting of forming the end of the lever with a protruding portion that shall come in contact with the underlying portion of a motor-arm, substantially as set forth.

7. In a label-addressing machine, the combination with a handle to be held in the palm of the hand and fastened upon the left side of the shell or supporting-frame with screws, of a belt-feeding roller, a thumb-balancer 130 formed from a stiff metallic plate and hinged upon the forward connecting-screw of the handle in rear of and in proximity to the belt-feeding roller and by so hinging made adjust-

able to the hand or fancy of the operator, substantially as set forth.

8. In an addressing-machine, provided with a web of addresses and a pasting-belt, the combination of a presser-bar adapted to be brought down upon the web of addresses in its passage to the pasting-belt, one end of said bar being bent at a right angle and hinged in

a bearing secured longitudinally at or upon the upper edge of the shell on the left side thereof, whereby the same can be swung into and out of action, substantially as set forth.

ALEXANDER DICK.
